Primary Examiner—M. N. Pandozzi*Attorney, Agent, or Firm*—Harold H. Dutton, Jr.; Diane F. Liebman[57] **CLAIM**

The ornamental design for a weighing dispenser, as shown and described.

DESCRIPTION

FIG. 1 is a perspective view of a weighing dispenser showing my new design;

FIG. 2 is a front view of the weighing portion of the weighing dispenser, the display portion being removed for ease of illustration;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view of the display portion of the weighing dispenser, the weighing portion being removed for ease of illustration;

FIG. 9 is a rear view thereof;

FIG. 10 is a left side view thereof;

FIG. 11 is a right side view thereof;

FIG. 12 is a top view thereof; and,

FIG. 13 is a bottom view thereof.

The broken line shown in FIG. 1 is for illustrative purposes only and forms no part of the claimed design.
